UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

FOURTH-POINT SUPPORT.

Application filed October 11, 1924. Serial No. 743,133.

This invention relates to new and useful improvements in fourth point supports for brake beams and the objects of the invention are to provide a support consisting of two separable members arranged to encircle the brake beam, one of said members being adapted to be quickly and easily detached so as to provide ready access to the brake beam for installation or repair purposes.

Further objects of the invention are to provide simple and effective means for inter-engaging the outer ends of said support members, thereby locking the removable member against displacement.

With these and other objects in view, my invention consists in certain novel features of construction and arrangement of parts, hereinafter more fully described and claimed, and illustrated in the accompanying drawings, in which—

Figure 1 is a side elevational view of the preferred form of the support.

Figure 2 is an end elevational view of the same.

Figure 3 is a side elevational view of a modified form of the invention.

Figure 4 is an end elevational view of the same.

Figure 5 is a side elevational view of another modified form of the improved support.

Figure 6 is a transverse cross section taken on line 6—6 of Figure 5.

Figure 7 is a side elevational view of a still further modified form of support.

Figure 8 is a perspective detail view of one end of the supporting member.

Figure 9 is a perspective detail view of one end of the track member.

Figure 10 is a horizontal cross section taken on line 10—10 of Figure 5.

The support constructed in accordance with my invention comprises two members which extend transversely of the brake beam above and below the same and have their outer ends detachably secured together, the opposite ends of said members being spaced from each other and in fixed relation with a car truck part. The lower member which forms the track for the forward end of the brake beam is made removable so that it can be readily detached and moved out of the way when installing or repairing the brake beam and also to permit replacement of said track member when worn or damaged.

Referring by numerals to the accompanying drawings, 10 indicates a car truck part, such as a spring plank, 11 indicates a compression member or rear end of the brake beam, and 12 the tension member or front end of the brake beam. A supporting member 14 is secured to the upper side of the spring plank by a bracket or strap 15 which is held in position by rivets or other fastening devices 16. Supporting member 14 is bent upwardly as at 14^a to clear the flanges of the spring plank and is then bent outwardly above the brake beam and terminates a suitable distance beyond the tension member 12. A lower or track member 17 has its inner or rear end 17^a slidably positioned in a seat formed by a bracket 18 which is secured to the underside of the spring plank. Member 17, after leaving the seat, drops downwardly as at 17^b in order to space it from the spring plank and extends outwardly under the brake beam, being provided with an inclined track portion 17^c which is slidably engaged and supports tension member 12 of the brake beam. The extreme end 19 of member 17 is bent to lie flat against the underside of the end of supporting member 14 and is locked thereto by a bolt and nut or other suitable attaching device 20.

The end of member 14 is provided with an aperture 21 for receiving the bolt and member 17 is provided with a longitudinally disposed slot 22 through which the bolt passes, said slot permitting automatic adjustment of the track member so that the latter may be properly seated and accommodate itself to the brake beam, and any inaccuracies in the proportions of the members being also thereby taken care of. The length of the slot is less than the length of portion 17^a so that the latter cannot be accidentally unseated but at the same time permitting sliding movement of the outer end of said track member with respect to said supporting member. After member 17 is in proper position, the nut and bolt connection 20 is locked against accidental disengagement by a pin 20^a or in any other suitable manner.

In the form shown in Figures 3 and 4, a supporting member 24 has its extreme end bent downwardly as at 24^a and formed therein is a slot 25 for the reception of the reduced end 26 of a track member 27. A cotter pin 28 is seated in the projecting portion of end 26 and prevents the withdrawal thereof from

the slot in the end 24^a. The reduced outer end 26 of the track member is of sufficient length to permit sliding movement of said end relative to the supporting member, it being necessary for said track member to have one end slidably in order to utilize the resiliency of said member.

In the preceding forms, both the supporting member and the track member are made flexible. However, if desired, the supporting member may be formed rigid as disclosed in Figures 5 and 6. In this form, which is similar in construction to the forms previously described, the supporting member 29 is formed rigid and is carried by spring plank 10 and has its outer end bent downwardly for engaging one end 26 of track member 27 the opposite end being secured to the spring plank.

In the forms shown in Figures 7 to 9, inclusive, the extreme end 30 of end supporting member 31 is provided with an aperture 32 in which is adapted to be seated a downwardly extending tongue or projection 34 formed on the rebent portion 35 of a track member 36. In this form, when the members are assembled together, the rear end of the track member is held in a seat formed on the underside of the spring plank and the forward end thereof is interlocked with the apertured end of the supporting member by means of tongue 34 occupying aperture 32. To remove track member 36 from position, the rebent portion 35 is pried away from the end 30 so as to bring tongue 34 out of engagement with aperture 32, whereupon track member 36 can be withdrawn from its position. Aperture 32 is of sufficient length to permit the rebent end to have sliding movement relative to said end 30. The tongue 34 occupying said aperture prevents disengagement of said interlocked ends.

A support of my improved construction is very simple and has its track portion formed detachable so that it can be easily removed from its position. The supporting member which is secured to the spring plank has its outer end adapted to enter into interlocking engagement with the corresponding end of the track member, thereby holding said track member against displacement. The resilient track member is slidably or yieldingly supported between said supporting member and said car truck part, preferably by having one or both of its ends in sliding interengagement with the respective support or supports. Thus any longitudinal movement of said track member, which movement is due to the resilient nature of said track member, is taken care of by the slidably mounted end thereof.

While I have shown and described the preferred forms of my invention, it will be readily understood that minor changes in the construction and arrangement of parts

of my improved support can be made and substituted for those herein shown, without departing from the spirit of my invention.

I claim:

1. A support for brake beams comprising a supporting member adapted to be fixedly mounted on a car part, and a track member having one end slidably engaged with the outer end of said supporting member and having its opposite end adapted to be seated in a seat provided on said car truck part. 70

75 2. A support for brake beams comprising a supporting member fixedly mounted in position on a car truck part, and a resilient track member having its inner end removably seated on said part and having its opposite end in adjustable engagement with the corresponding end of said supporting member, and removable means for locking said track member against displacement. 80

85 3. A support for brake beams comprising a supporting member adapted to be fixed to a car truck part and arranged to extend over and above a brake beam, and a resilient track member adapted to be disposed under said brake beam and having its inner end seated under said car truck part and having its outer end adjustably held in engagement with one end of said supporting member. 90

95 4. A support for brake beams comprising a supporting member adapted to be fixed to a car truck part and arranged to extend over and above a brake beam, a resilient track member adapted to be disposed under said brake beam and having its inner end slidably seated under said car truck part, and means for slidably interlocking the outer ends of said members. 100

105 5. A support for brake beams comprising a supporting member extending over a brake beam and carried by a car truck part, and a resilient track member disposed under said brake beam and having one end in sliding engagement with said car truck part for permitting resilient movement of said track member and having its opposite end in interlocking engagement with the other end of said supporting member. 110

115 6. In a brake beam support, the combination with a car truck part, of a pair of removable members disposed above and under a brake beam, respectively, one of said members having a fixed engagement with said car truck part and the other member having a separate detachable engagement therewith, the opposite ends of said members having adjustable interengagement with each other for permitting independent longitudinal movement thereof. 120

125 7. In a car truck construction, the combination with a car truck part, of a supporting member carried by said car truck part, and a track member in sliding engagement with said car truck part and with said supporting member. 130

8. In a car truck construction, the combination with a car truck part, of a supporting member carried by said car truck part, a track member in sliding engagement with said car truck part and with said supporting member, and a member for locking one end of said track member to the corresponding end of said supporting member.

9. In a brake beam support, the combination with a car truck part, of a supporting member carried by said car truck part, and a resilient track member having its ends detachably interengaged with said car truck part and the outer end of said supporting member, respectively, one of the ends of said track member having sliding interengagement with its respective supporting part, whereby said track member is permitted a certain degree of movement required by the resilient nature of said track member.

10. In a brake beam support, the combination with a car truck part, of a supporting member carried by said car truck part, and a resilient track member having its ends detachably interengaged with said car truck part and the outer end of said supporting member, respectively, one of the ends of said track member having sliding interengagement with its respective supporting part, whereby said track member is permitted a certain degree of movement required by the resilient nature of said track member, and means for locking said track member against displacement.

11. In a brake beam support, a supporting member and a track member having their outer ends slidably interengaged and their opposite ends adapted to be carried by a car truck part, one of said members being resilient to render said support yielding.

12. A third or fourth point support for brake beams comprising in combination with a car truck part, a supporting member mounted on said car truck part, and a resilient track member for supporting a brake beam, said track member being supported at its respective ends by said supporting member and said car truck part, one of said ends having slidable engagement with its respective supporting part for operatively utilizing the resiliency of said track member.

13. A third or fourth point support for brake beams comprising in combination with a car truck part, a supporting member mounted on said car truck part and a resilient track member for supporting a brake

beam, said track member being supported at its respective ends by said supporting member and said car truck part, one of said ends having slidable engagement with its respective supporting part for operatively utilizing the resiliency of said track member, and means for locking said track member against displacement.

14. A brake beam support comprising a yielding member adapted to be fixedly secured to a car part and to extend therefrom over a brake beam, and a yielding member adapted to be slidably secured at one end to said car part and to extend therefrom under said brake beam and to be attached to said first mentioned member.

15. A brake beam support comprising a yielding member adapted to be fixedly secured to a car part and to extend therefrom over a brake beam, and a yielding member adapted to be slidably secured at one end to said car part and to extend therefrom under said brake beam and to be adjustably attached to said first mentioned member.

16. In a brake beam support, a yielding member adapted to extend outwardly from a car part over a brake beam and having a perforated outer end, a second yielding member adapted to extend outwardly from said car part and having a slotted outer end, and a bolt passing through the perforation and slot in the outer ends of said members and adjustably securing said members to each other.

17. In a brake beam support, a support member adapted to be secured to a truck part and to extend outwardly therefrom over a brake beam, a second member adapted to be secured to said car part and to extend outwardly therefrom under the brake beam, means securing the outer ends of said members to each other, said second mentioned member being removable from said first mentioned member without removing the latter from said car part.

18. In a brake beam support, a truck part, support members extending outwardly therefrom above and below the brake beam respectively, independent means securing each of said members to said truck part, and detachable means securing the outer ends of said members to each other.

In testimony whereof I hereunto affix my signature this 6th day of October, 1924.

EDWIN G. BUSSE.
